UNITED STATES PATENT OFFICE.

WILLIAM H. BITTNER, OF BLOOMFIELD, NEW JERSEY, ASSIGNOR TO THE CONSOLIDATED SAFETY PIN COMPANY, OF SAME PLACE.

DESIGN FOR A SAFETY-PIN.

SPECIFICATION forming part of Design No. 33,120, dated August 28, 1900.

Application filed June 27, 1900. Serial No. 21,850. Term of patent 14 years.

To all whom it may concern:

Be it known that I, WILLIAM H. BITTNER, a citizen of the United States, residing in Bloomfield, in the county of Essex, State of New Jersey, have invented and produced a certain new and original Design for a Safety-Pin, of which the following is a specification, reference being had to the accompanying drawings, forming a part hereof.

This invention relates to safety-pins; and it consists in the design therefor shown in the accompanying drawings, in which—

Figure 1 is a side view of a safety-pin which embodies the design, and Fig. 2 is an edge view thereof as seen from above in Fig. 1.

The point member *a*, the coil *b* at one end, and the hood or shield *c* at the other end present substantially the usual appearance; but the back member *d*, as seen in Fig. 1, presents the appearance of a series of inclined flattened faces *e*, with substantially parallel

sides and rounded ends, such faces being slightly separated one from another. Said back member when seen in edge view, as shown in Fig. 2, presents the appearance of a series of elongated beads *f*, with their longer axes obliquely disposed. From a point near the end of the back member *d* is a short member *g* with flattened face, extended obliquely toward the other side of the hood or shield *c*.

The characteristic feature of the design is the series of inclined flattened faces *e* with substantially parallel sides.

I claim as my invention—

The design for a safety-pin, substantially as shown and described.

This specification signed and witnessed this 25th day of June, A. D. 1900.

WM. H. BITTNER.

In presence of—

GEO. P. FARMER,
NELLIE E. MATTHEWS.
